RAILWAY TRAFFIC CONTROLLING APPARATUS

Filed March 18, 1930

UNITED STATES PATENT OFFICE

JAMES J. VANHORN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed March 18, 1930. Serial No. 426,743.

My invention relates to railway traffic controlling apparatus, and particularly to apparatus for single track, involving manually controlled switches and manually controlled signals governing traffic over such switches.

One feature of my invention is the provision, in systems of this kind, of a single relay provided with a single line circuit and serving as a home relay for one direction of traffic, and as a relay for the control of approach locking for the other direction of traffic.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a railway track Q over which traffic moves in both directions. These rails are divided by insulated joints 3 to form a stretch of track X—Y, and the rails of this stretch are further divided by similar joints to form track sections X—U, U—V and V—Y. A signal S¹, located at point Y, governs westbound traffic through this stretch, and a signal S², located at the point X, governs eastbound traffic through the stretch. Located at the point U is a second westbound signal S³, governing traffic through the section X—U and the track to the west of this section. Located at the point V is a second eastbound signal S⁴, governing traffic through section V—Y and the track to the east of this section. Located in the station V—Y is a switch C^A arranged when reversed to divert westbound traffic into a side track M. Located in the section X—U is a switch C^B arranged when reversed to divert eastbound traffic into the same side track. The switch C^B is operated by a mechanism G^B, and the switch C^A is operated by a similar mechanism which is omitted from the drawing.

Each track section is provided with a track circuit comprising the usual track battery 2 and track relay T.

The signals S¹ and S⁴ are controlled by a polarized relay P^A, and the signals S² and S³ are controlled by a similar polarized relay P^B. Switch C^B is controlled by a polarized switch relay F^B, and a similar relay, not shown in the drawing, will ordinarily be provided for the control of switch C^A. The apparatus at the western end of the stretch is controlled in part by a line relay H^B, and a similar relay H^A is provided for the apparatus at the other end of the stretch. Associated with the relay H^B is a stick relay D^B, and a slow pick-up relay E^B. The polarized relays F^B, P^B and P^A are controlled in any suitable manner from a central point W, such, for example, as a despatcher's office, and as here shown, these relays are controller by pole-changers L^B, K^B and K^A, respectively.

As shown in the drawing, pole-changers K^A and K^B are in their middle positions, so that relays P^A and P^B are deenergized, with the result that all four of the signals indicate "stop". Pole-changer L^B is in its normal position, so that relay F^B is energized in the normal direction, with the result that switch C^B is likewise in its normal position. The stretch X—Y is unoccupied, so that all the track relays T are energized. Line relay H^B is energized by virtue of a circuit which passes from terminal X of a suitable source of current, through the back point of contact 13 of signal relay P^A, contact 14 of track relay T¹, contact 15 of track relay T², and the winding of relay H^B to terminal 0 of the same source of current. Relay H^A is energized by a similar circuit including the back point of contact 18 of signal relay P^B and contacts 19 and 20 of track relays T¹ and T². Relay H^B being energized, relay D^B is energized by virtue of a pick-up circuit which includes a front contact 30 of relay H^B. Relay E^B is deenergized, because its circuit is open at the back point of contact 32 of relay D^B.

I will now assume that the despatcher desires to clear signals S¹ and S² to permit a westbound train to pass along the main track Q. To do this, he will operate pole-changers K^A and K^B to supply current of such relative polarity to relays P^A and P^B that the polar

contacts of these relays will swing to the left. A circuit for signal S^1 will then be closed, which circuit is from terminal X, through contact 8 of track relay T^3 , contact 9 of a circuit controller N^A operated by switch C^A and which contact is closed only when the switch is in the normal position, neutral front contact 10 of relay P^A , polar contact 11 of this relay in the left-hand position, contact 12 of relay H^A , and the operating mechanism of signal S^1 to terminal 0. Signal S^3 will also move to the clear position by virtue of a circuit which passes from terminal X, through contact 3 of track relay T^1 , normal contact 4 of a circuit controller N^B operated by switch C^B , neutral contact 5 of relay P^B , polar contact 6 of this relay in the left-hand position, and the operating mechanism of signal S^3 to terminal 0. Relay H^B will now become deenergized, because its circuit is open at the back point of contact 13 of signal relay P^A . When the train passes signal S^1 , this signal will be returned to the stop position, because of the fact that its circuit will be opened at contact 8 of track relay T^3 . When the train passes signal S^3 , this signal will, likewise, return to the stop position, because its operating circuit will be opened at contact 3 of track relay T^1 .

It will be noted that the operating circuit for signal S^1 includes a front contact 12 of the line relay H^A . This relay remains energized because its circuit is provided with a branch around the back point of contact 18 of relay P^B , which branch includes a front point of this contact and polar contact 21 of the same relay, which polar contact is closed when the relay is energized in such direction as to clear signal S^3 .

If the despatcher desires to permit an eastbound train to proceed along the main track, he will move pole-changers K^A and K^B to their opposite positions, thereby energizing relays P^A and P^B by current of the other relative polarity. Signal S^2 will then give a proceed indication by virtue of a circuit which includes contact 3 of track relay T^1 , normal contact 4 of circuit controller N^B , neutral contact 5 of relay P^B , polar contact 6 in the right-hand position and contact 7 of relay H^B . Signal S^4 will assume the proceed indication by virtue of a circuit which includes contact 8 of track relay T^3 , normal contact 9 of circuit controller N^A , neutral contact 10 of relay P^A and polar contact 11 of this relay in the right-hand position. It will be observed that the circuit for signal S^2 includes contact 7 of relay H^B ; this relay will remain energized by virtue of a branch for its circuit around the back point of contact 13 of relay P^A , which branch includes the front point of this contact and the polar contact 16 in the right-hand position. Relay H^A will become deenergized, because its circuit will be opened at the back point of contact 18 of

relay P^B . The operation of the apparatus as such train passes through the stretch will be obvious without further explanation.

If the despatcher desires to reverse switch C^E , he will reverse the position of pole-changer L^B , thereby supplying current of reverse polarity to relay F^B , the circuit being from terminal X, through the upper contact of pole-changer P^B , contact 29 operated by signal S^3 and closed only when this signal is in the stop position, contact 28 similarly operated by signal S^2 , contact 27 of track relay T^1 , winding of relay F^B , contact 26 of relay D^B , and the lower contact of pole-changer L^B to terminal 0. By virtue of the contacts 28 and 29 operated by signals S^2 and S^3 , respectively, it will be obvious that the switch cannot be reversed unless both of these signals indicate stop. It is also obvious that the switch cannot be reversed unless relay D^B is energized, because of the front contact 26 of this relay which is included in the circuit for relay F^B . The operation of the apparatus to restore switch C^E to its normal position will be apparent without further explanation.

I will now assume that westbound signals S^1 and S^3 have been cleared, that a westbound train is in the section U—V, and that the despatcher desires to stop such train and reverse the switch C^B . Relay H^B is deenergized, because its circuit is open at contact 15 of track relay T^2 , and relay D^B is deenergized because its main pick-up circuit is open at contact 30 of relay H^B , its auxiliary pick-up circuit is open at contact 33 of relay E^B , and its stick circuit is open at contact 31 operated by signal S^3 . It follows that the circuit for relay F^B is open at contact 26 of relay D^B , as well as at contact 29 of signal S^3 , and so the switch cannot be reversed. In order to reverse the switch, the despatcher will first operate pole-changer K^B to deenergize P^B , thereby placing signal S^3 at stop. A circuit for relay E^B will then be closed, which circuit passes from terminal X, through contact 31 operated by signal S^2 and closed only when this signal indicates stop, back point of contact 32 of relay D^B , and the winding of relay E^B to terminal 0. After the lapse of time required for relay E^B to close its front contact, the auxiliary pick-up circuit for relay D^B will become closed, which circuit passes from terminal X, through contact 31 on signal S^3 , contact 33 of relay E^B , and the winding of relay D^B to terminal 0. As soon as relay D^B becomes energized, relay E^B will become deenergized, but relay D^B will remain energized by virtue of its stick circuit which passes from terminal X, through contact 31 on signal S^3 , front point of contact 32 of relay D^B , and the winding of this relay to terminal 0. The circuit for switch relay F^B will then be closed at all points, so that this switch

may be reversed to permit an eastbound train to enter the side track M.

I will now assume that with all parts of the apparatus in their normal conditions, as shown in the drawing, the despatcher reverses switch C^B. This will close another branch for the circuit of line relay H^A around the contacts of track relay T¹ and signal relay P^B, which branch passes from terminal X, through contact 22 of circuit controller N^B to contact 20 of track relay T². Relay P^B may then be energized in such direction as to clear signal S² without deenergizing relay H^A, with the result that signal S¹ may be moved to the proceed position to permit a westbound train to enter track section V—Y.

The circuit for relay H^B is provided with a similar branch including normally open contact 17 of switch-operated circuit controller N^A.

It will be seen from the foregoing that the line relay H^B serves as a home relay for signal S² during eastbound train movements, and that it also serves as a means for controlling the approach locking of switch C^B during westbound train movements. Line relay H^A serves a similar function in so far as concerns signal S¹ and switch C^A.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track divided into sections, track circuits including track relays for said sections, a switch C^A in the track section at the east end of said stretch and a switch C^B in the track section at the west end of said stretch, a westbound signal S¹ and an eastbound signal S² governing traffic into said stretch, a westbound signal S³ governing traffic into the track section at the west end of said stretch, an eastbound signal S⁴ governing traffic into the track section at the east end of said stretch, a polarized relay P^A for the control of signals S¹ and S⁴, a polarized relay P^B for the control of signals S² and S³, a home relay H^B associated with said signals S² and S³ and having a front contact included in the control circuit for signal S², a circuit for relay H^B including front contacts of all of said track relays except the one for the section at the west end of said stretch and a back contact of relay P^A, a branch for said circuit around the back contact of relay P^A and including a front contact of relay P^A and a polar contact of relay P^A closed when the relay is energized to clear signal S⁴, a stick relay D^B, a slow pick-up relay E^B, a pick-up circuit for relay D^B including a front

contact of relay H^B, a stick circuit for relay D^B including a contact closed only when signal S³ indicates stop, a second pick-up circuit for relay D^B including said signal contact and a front contact of relay E^B, a circuit for relay E^B including said signal contact and a back contact of relay D^B, a relay F^B for the control of switch C^B, and controlling means for relay F^B including a front contact of relay D^B.

2. In combination, a stretch of railway track divided into sections, track circuits including track relays for said sections, a switch C^A in the track section at the east end of said stretch and a switch C^B in the track section at the west end of said stretch, a westbound signal S¹ and an eastbound signal S² governing traffic into said stretch, a westbound signal S³ governing traffic into the track section at the west end of said stretch, an eastbound signal S⁴ governing traffic into the track section at the east end of said stretch, a polarized relay P^A for the control of signals S¹ and S⁴, a polarized relay P^B for the control of signals S² and S³, a home relay H^B associated with said signals S² and S³ and having a front contact included in the control circuit for signal S², a circuit for relay H^B including front contacts of all of said track relays except the one for the section at the west end of said stretch and a back contact of relay P^A, a branch for said circuit around the back contact of relay P^A and including a front contact of relay P^A and a polar contact of relay P^A closed when the relay is energized to clear signal S⁴, and means for controlling said switch C^B by said relay H^B.

3. In combination, a stretch of railway track divided into sections, track circuits including track relays for said sections, a switch C^A in the track section at the east end of said stretch and a switch C^B in the track section at the west end of said stretch, a westbound signal S¹ and an eastbound signal S² governing traffic into said stretch, a westbound signal S³ governing traffic into the track section at the west end of said stretch, an eastbound signal S⁴ governing traffic into the track section at the east end of said stretch, a polarized relay P^A for the control of signals S¹ and S⁴, a polarized relay P^B for the control of signals S² and S³, a home relay H^B associated with said signals S² and S³ and having a front contact included in the control circuit for signal S², a circuit for relay H^B including front contacts of all of said track relays except the one for the section at the west end of said stretch and a back contact of relay P^A, a branch for said circuit around the back contact of relay P^A and including a front contact of relay P^A and a polar contact of relay P^A closed when the relay is energized to clear signal S⁴, and means for controlling said switch C^B by said relay H^B.

4. In combination, a stretch of railway track divided into sections, track circuits including track relays for said sections, a switch C^A in the track section at the east end of said stretch and a switch C^B in the track section at the west end of said stretch, a westbound signal S¹ and an eastbound signal S² governing traffic into said stretch, a westbound signal S³ governing traffic into the track section at the west end of said stretch, an eastbound signal S⁴ governing traffic into the track section at the east end of said stretch, a polarized relay P^A for the control of signals S¹ and S⁴, a polarized relay P^B for the control of signals S² and S³, a home relay H^B associated with said signals S² and S³ and having a front contact included in the control circuit for signal S², a circuit for relay H^B including front contacts of all of said track relays except the one for the section at the west end of said stretch and a back contact of relay P^A, a branch for said circuit around the back contact of relay P^A and including a front contact of relay P^A and a polar contact of relay P^A closed when the relay is energized to clear signal S⁴, a stick relay D^B, a slow pick-up relay E^B, a pick-up circuit for relay D^B including a front

contact of relay H^B, a stick circuit for relay D^B including a contact closed only when signal S³ indicates stop, a second pick-up circuit for relay D^B including said signal contact and a front contact of relay E^B, a circuit for relay E^B including said signal contact and a back contact of relay D^B, a relay F^B for the control of switch C^B, and controlling means for relay F^B including a front contact of relay D^B.

5. In combination, a stretch of railway track divided into sections, track circuits including track relays for said sections, a switch C^A in the track section at the east end of said stretch and a switch C^B in the track section at the west end of said stretch, a westbound signal S¹ and an eastbound signal S² governing traffic into said stretch, a westbound signal S³ governing traffic into the track section at the west end of said stretch, an eastbound signal S⁴ governing traffic into the track section at the east end of said stretch, a polarized relay P^A for the control of signals S¹ and S⁴, a polarized relay P^B for the control of signals S² and S³, a home relay H^B associated with said signals S² and S³ and having a front contact included in the control circuit for signal S², a circuit for relay H^B including front contacts of all of said track relays except the one for the section at the west end of said stretch and a back contact of relay P^A, a branch for said circuit around the back contact of relay P^A and including a front contact of relay P^A and a polar contact of relay P^A closed when the relay is energized to clear signal S⁴, a second branch in the circuit for relay H^B

around the contacts of relay P^A and the contact of the track relay for the sections at the east end of said stretch which branch includes a contact closed only when switch C^A is reversed, and means for controlling said switch C^B by said relay H^B.

In testimony whereof I affix my signature.
JAMES J. VANHORN.
